UNITED STATES PATENT OFFICE.

KARL ARNSTEIN, OF FRIEDRICHSHAFEN, GERMANY.

SKELETON FRAME CONSTRUCTION FOR AIRSHIPS AND THE LIKE.

Application filed April 8, 1922. Serial No. 550,885.

To all whom it may concern:

Be it known that I, KARL ARNSTEIN, a citizen of Czechoslovakia, residing at Fried-
richshafen, A. B., Germany, have invented
5 certain new and useful Improvements in
Skeleton Frame Construction for Airships
and the like, of which the following is a
specification.

My invention has reference to an im-
10 proved manner of constructing rigid sup-
porting frames for air ships and the like by
means of which the construction of frames
of this kind is considerably facilitated.

The frames of air ships of the rigid type
15 were originally constructed merely of rings
and longitudinal supporting members con-
necting the same. With the increase in size
of the ship and the increase of the distance
between the rings it became necessary to
20 provide means for diminishing the freely
exposed length of the span between the longi-
tudinal supports by intermediate auxiliary
supporting members, and in view of this it
has been suggested to provide semi-circular
25 or circular rings in the lower portion of the
hull arranged intermediate the longitudinal
supporting members, so as to subdivide the
space between them and to secure greater
resisting capacity against the pressure of the
30 enclosing shell when the hull was empty.
Such auxiliary rings are of great impor-
tance, inasmuch as by this means it becomes
impossible to increase the distance between
the supporting rings without necessitating
35 an increase of the exposed unsupported
length of the longitudinal supporting mem-
bers.

It is an object of my invention to provide
means for avoiding the necessity of sidewise
40 insertion of such auxiliary rings on the rigid
supporting frame as practised heretofore,
which method entails great expenses and
labor, and with this purpose in view I pro-
vide means for manufacturing the auxiliary
45 rings in the same manner as the supporting
ring upon the floor of the hall of construc-
tion by the utilization of temporary stiffen-
ing means, and I am thereby enabled, when
the structure is set up, to connect the aux-
50 illary rings to the longitudinal supports in
a similar manner as the main supporting
rings.

By means of this invention a great number
of auxiliary or intermediary rings may be

employed with the additional advantage 55
that with a sufficient number of such rings
the load on each ring is so small and the
stress on the longitudinal supporting mem-
ber becomes so favorably distributed that
specially constructed supports or truss beams 60
are wholly or to a large extent avoided, so
that one is able to make use of ordinary
flanged supporting beams.

In the drawings affixed to this specifica-
tion and forming part thereof a structure 65
embodiment my invention is illustrated dia-
grammatically by way of example.

Figure 1 shows in a conventional man-
ner a portion of the hull structure of an air
ship seen from the side, 70

Figure 2 is a cross section.
The skeleton frame of the hull comprises
longitudinal supports a^1 , a^2 , a^3 , a^4 , etc., to
 a^{13} , and supporting rings b^1 and b^2 . Be-
tween the said rings three auxiliary rings 75
 c^1 , c^2 , and c^3 are arranged in such a manner
that these auxiliary rings are manufactured
in any suitable place or manufacture as
closed rings that are proof against bending
and deflection; they are then provided with 80
temporary stiffening or tensional members d .
The auxiliary rings are then connected to
the longitudinal supports, whereupon the
temporary stiffening members are removed.
The stiffening of the fields formed by the 85
longitudinal supports a^1 to a^{13} may be effect-
ed for example in the manner illustrated in
Figure 1 by means of wires e which extend
diagonally through the fields from one point
of juncture to the other. 90

I wish it to be understood that I do not
desire to be limited to the exact details of
constructions shown and described, as many
obvious modifications will occur to a person
skilled in the art. 95

I claim:
The method of making rigid skeleton
frames for air ships which consists in con-
necting parallelly spaced longitudinal sup-
porting members to a transversely arranged 100
supporting ring, bracing an auxiliary ring
by aid of radial tension members, inserting
said auxiliary ring intermediate, said sup-
porting members parallel to said supporting
ring and removing said radial tension mem- 105
bers.

In testimony whereof I affix my signature,
KARL ARNSTEIN,
